REVOLVING-SEAT DAVENPORT.

1,135,930.

Specification of Letters Patent. Patented Apr. 13, 1915.

Application filed August 15, 1910. Serial No. 577,269.

To all whom it may concern:

Be it known that we, WENDELIN P. SENG and JOSEF KALTCKOK, citizens of the United States, and residents of the city of Chicago, in the county of Cook and State of Illinois, have invented certain new and useful Improvements in Revolving-Seat Davenports; and we do hereby declare that the following is a full, clear, and exact description of the same, reference being had to the accompanying drawings, and to the numbers of reference marked thereon, which form a part of this specification.

This invention has for its object an improvement in the revolving seat sofa bed or davenport for which United States Letters Patent No. 848,305, was issued to G. E. Holmes, A. G. Bostrom and J. M. Bostrom, on the 26th day of March, 1907.

The object of the invention is to afford certain improvements in the construction of such devices in respect to the locking mechanism, as will be hereinafter more definitely pointed out and claimed, reference being had to the accompanying drawings, in which—

Figure 1 is a transverse section taken at the end of the couch or bed and showing the same in its folded position. Fig. 2 is a similar view showing the same in its open or extended position. Fig. 3 is a longitudinal sectional view on the line 3—3 of Fig. 1, showing the couch seat inverted and the parts in position for the opening of the bed. Fig. 4 is an enlarged fragmentary detail of the lock shown in Fig. 3. Fig. 5 is a fragmentary section on line 5—5 of Fig. 4. Fig. 6 is an enlarged detail of the locking mechanism showing the same in locking position. Fig. 7 is a section taken on line 7—7 of Fig. 6. Fig. 8 is an enlarged fragmentary detail and face view showing the locking plate.

As shown in the drawings: the bed comprises any suitable frame such as are usual for davenports or the like, comprising a permanent back 1, and end members 2, which are connected longitudinally at the rear to afford a rigid structure, said end members or arms 2, being also connected with the back 1, to afford the requisite strength. Beneath said end members are provided casters 3, and secured on each of the end members is a pivot plate having means thereon for receiving therethrough the flanged head of the pivot pin 7, secured in the complemental

pivot plate 8, which, as shown, in Figs. 1 and 2, is secured to the bed frame. Said pivot pin 7, is secured near the inner end of the pivot plate 8, when adjusted in the couch position, as shown in Fig. 1, and extending from a point below said pivot pin is a cycloidally curved slot which terminates near the upper edge and opposite end of said plate, as shown in Fig. 1, and at said upper end of the slot is extended outwardly substantially horizontally affording a shoulder 10, jutting into the slot.

Secured on the pivot plate, in position to engage in the slot in the complemental pivot plate is a pin 11, as shown cylindric in form and of a diameter approximating the width of the slot and adapted when the bed is folded inwardly and adjusted as shown in Fig. 1, to seat in the opposite portion of the slot above the shoulder 10, to positively hold said portion from turning inwardly because of any weight upon the rear side thereof.

Secured upon the seat 12, which, of course, may be of any desired construction, at the front edge thereof is a downwardly projecting plate 50, which coincides with the front of the couch when in the position shown in Fig. 1, and conceals the mechanism and which extends upwardly along the upholstered back when the bed is opened, as shown in Fig. 2.

Supported upon the seat frame are downwardly directed straps 13, of metal riveted thereto at the inner edge of said frame and on each of which is pivotally engaged a relatively short bed frame section 14, which extends equally on opposite sides of said strap 13, and is hingedly connected with complemental end frame sections 15 and 16, the former of which is pivotally engaged on a link 17, connected therewith and with the seat frame of said couch, as shown in Figs. 1 and 2. The latter of said frame members at each end of the couch or bed is provided near its extremity with a leg 18, which is pivoted thereto near its upper end and is of a length to rest upon the floor when the couch is extended horizontally, as shown in Fig. 2. The upper end of said leg extends slightly above said bed frame and connected therewith and with the pivot pin at the upper end of the strap 13, is a link or bar 19.

A side bar 51, connects the outer ends of sections 16, and a bar connects the outer

ends of sections 15 which complete the bed frame. And secured to said frame is a spring wire fabric of any suitable kind or character. Said fabric, being constructed 5 of parallel spring engaged longitudinal wires or members, and transverse wires or members which permit the bed frame to fold at the pivotal section or at the hinges afforded between the frame members 14, 15, 10 and 16. As shown, said frame members are constructed of structural steel, as, for instance, angle bars, and the webs and flanges thereof are so engaged together that when the frame section 16, is turned upwardly at 15 a right angle with the short pivotally supported section 14, the flanges of sections 14 and 16, lock, which causes the section 14, to rotate until the flanges on the sections 14 and 15, mutually engage so that the sections 20 15 and 16, when the bed is closed are parallel and the leg 18, is folded inwardly thereby to the position shown in Fig. 1. When so folded the bed frame or mattress frame affords a receptacle beneath the cushion 25 adapted to contain all the bedding necessary when the bed is extended. Means are provided for locking the inner edge of the bed frame in supporting position when said bed is fully opened out for use, and also for 30 locking or securing the bed frame in folded position while inverting the same. For this purpose, as shown, rods 20, 21 and 22, are secured transversely the bed frame on the front side thereof when the bed frame is 35 folded to the position shown in Fig. 1, said rods having hooked ends to engage the sections 15 and 16, of the bed frame together, to hold the same while rotating the couch seat. The upper ends of said rods 20 and 40 22, as shown in Fig. 9, are each bent to afford an outwardly directed arm 23, each of which pivotally engages a bolt 24, each of a length slightly greater than half of the couch seat or cushion. The inner ends 45 of said bolts are pivotally connected on a link 25, rigidly secured on the end of the locking rod 21, as shown in Fig. 5, so that the rotation of said rod 21, in either direction actuates said bolts either to extend or 50 retract the same into engagement with the locking plates 27, secured on the couch ends, as shown in Fig. 3, or to retract the same to permit free rotation of the bed. From the construction described, obviously said bolts 55 may be operated by utilizing either of said rods therefor, using the upper hooked end therefor as a crank for that purpose.

The operation is as follows: With the couch adjusted as shown in Fig. 1, in which 60 the bedding is inclosed within the bed frame, the operator lifts the front edge of the couch, drawing the same very slightly outwardly to release the pin 11, from the shoulder 10, in the curved slot in the pivot plates 65 and inverts the couch. In this position the

locking bolts before described are disposed along the rear edge of the bed frame and may be released by engaging either of the same and swinging the bolts to the position shown in Fig. 3, in which position the bolts 70 are shot into the apertures in the straps 27, on the end frames of the couch, thus rigidly holding the inner end of the bed frame in adjusted position. The operator now reaches over and engages the inner edge of 75 the outer folding section of the bed frame or that corresponding with the end members 16, of the bed frame and swings the same over to the position shown in Fig. 2, such movement acting to lift the tilting section 80 to horizontal position and elevating the inner edge of the bed frame upon the pivotally engaged links 17, thus elevating the bed as a whole to a horizontal position and affording a continuous supporting spring surface without intermediate bars or rails. 85

The outer swing of the outer bed section serves to swing the legs 18, downwardly to supporting position, as shown in Fig. 2, inasmuch as the radial distance between the 90 pivotal connection of the leg on the end frame member 16, and the inner pivotal connection of the link 19, is materially increased. In this position the bed is firmly supported and securely locked from movement. When it is desired to close the same the outer edge of the outer folding section of the bed frame is lifted and turned over upon the inner frame section. This movement necessitates the tilting of the short intermediate section 14, when the end frame members 16, are at a right angle with said intermediate frame members and these in turn when at a right angle with the inner frame members, 15, are limited from further 100 movement relative thereto. In consequence, all the bedding is inclosed in the receptacle thus formed and when the outer section is turned inwardly parallel the inner, the hooks at the upper ends of the locking rods 110 20, 21 and 22, are turned inwardly over the same, thus retracting the bolts and leaving the bed free to turn to its normal position as a couch, as shown in Fig. 1, and in this position, as before described, the offset or 115 shoulder 10, projecting into the slot serves as a positive lock to maintain the couch in operative position.

Of course, details of the construction may be varied, as, for instance, other means may 120 be provided for locking the sections of the bed frame in closed position and when released therefrom locking the open bed in its extended position. We have, however, shown but a preferred form of our invention and we therefore do not purpose limiting ourselves otherwise than necessitated by the prior art.

We claim as our invention:

1. In a device of the class described, the 130

combination with a back and side members, of a seat pivotally connected to the side members, a folding bed-frame section pivoted to said seat, oppositely movable locking 5 bolts secured to said seat, a link pivotally connecting the inner ends of said locking bolts, a rod rigidly secured to said link for operating the latter to project or retract said bolts with respect to said side members re- 10 spectively, and rods connected to said locking bolts and having angled ends adapted to engage and bind together the sections of the bed-frame when folded, said rods being adapted to shift said bolts to locking or re- 15 tracted position, and said side members and locking bolts being formed and arranged for mutual engagement when said bolts are projected for locking the seat.

2. A device of the class described comprising a stationary frame having side members, a seat pivotally connected to said side mem- 20

bers, and a folding bed bottom carried on the reverse side of said seat, in combination with a locking bolt secured to said seat and movable outwardly to engage one of said 25 side members, and a plurality of spaced rods disposed transversely of said seat and connected turnably to said locking bolt and having shouldered ends adapted to engage and lock together the sections of the bed bottom 30 when folded, said rods being formed and adapted for shifting said bolt to locking or retracted position in releasing and locking the bed bottom respectively.

In testimony whereof we have hereunto 35 subscribed our names in the presence of two subscribing witnesses.
